(57) **CLAIM**

I claim the ornamental design for a panel for enclosure, wall, or the like, as shown and described.

DESCRIPTION

FIG. 1 is a perspective view of a panel for enclosure, wall, or the like showing our new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is yet another perspective view thereof, shown in the environment of additional panels assembled as an enclosure. The broken lines adjacent shaded areas represent bounds of the claimed design and illustrate features of the panel for enclosure, wall, or the like that form no part of the claimed design. All other broken lines illustrate features of the panel for enclosure, wall, or the like that form no part of the claimed design.

The broken lines of the additional panels in FIG. 9 are directed to environment and form no part of the claimed design.
